UNITED STATES PATENT OFFICE.

WILLIAM W. DEAN, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

TELEPHONE-EXCHANGE SYSTEM.

1,169,320.

Specification of Letters Patent.

Patented Jan. 25, 1916.

Application filed May 20, 1907. Serial No. 374,754.

To all whom it may concern:

Be it known that I, WILLIAM W. DEAN, citizen of the United States, residing at Elyria, in the county of Lorain and State 5 of Ohio, have invented certain new and useful Improvements in Telephone-Exchange Systems, of which the following is a specification, reference being had therein to the accompanying drawing.

10 My invention relates to telephone exchange systems, and has for its object to provide means whereby the clearing-out or cutting-off of connected lines and the control of the connective circuits is effected 15 by certain acts of the calling and called subscriber jointly.

My invention is in its nature generic, and is intended to be applied either to automatic or to manual exchange systems. In 20 both cases its operation is essentially the same, and I shall therefore make broad claims in the present case.

In Patent No. 854,279 of May 21, 1907, I have described and claimed a specific form 25 of this invention as applied to manual exchange systems only. In the present application therefore, in addition to claiming broadly the principal features irrespective of the type of system in which they are 30 incorporated, I shall specifically claim their embodiment in an automatic connecting circuit.

Broadly stated, my invention contemplates the making of a call by a telephone 35 subscriber and the completion of the connection at the central office, with one other succeeding act required either on the part of the calling or of the called subscriber, before the connection can be taken down or 40 cleared out by a subscriber. Of course, a connection can be cleared out by an operator at any time, but my invention relates directly to an automatic clearing-out apparatus controlled by the subscriber.

45 My invention is illustrated in the accompanying drawings, wherein the figure is a diagram showing my invention as applied to an automatic connector circuit having automatic ringing.

50 A' indicates the vertical relay of a Strowger automatic switch such as that

shown in the patent to Keith and Erickson, 815,176, granted March 13, 1906.

C' indicates the rotary relay and a' and c' denote the rotary and vertical magnets respectively.

P' denotes the private relay controlling the side switches shown at s', s², s³ and s⁴.

B denotes the main battery.

U' indicates the spindle, w and w' indicate the wipers carried thereby, while d and d' indicate the contacts. The test wiper t' is arranged as shown in the figure.

R' denotes the release magnet.

At each subscriber's station there is provided a sender of the usual Strowger type which may be operated by the subscriber to send a predetermined number of impulses over the line according to the number set up on the dial, this being the ordinary procedure in operating an automatic connecting circuit of this kind. I have indicated this sender by the pair of keys D and D'.

The relay S is provided with a pair of armatures e and e', the operation of the relay 75 depending on mechanism hereinafter described.

An automatic ringing device consisting of a generator G' and an interrupter H' is arranged to furnish ringing current which 80 may be projected upon the lines by the closing of the contacts x' and z' through the armatures of the relay J'. In series with the relay J' is a slow acting relay K provided with a dashpot L' which is so arranged that when the magnet of the relay 85 K' is energized its armature will be slowly pulled up.

A choke coil M' is connected between the tip and sleeve sides of the calling end of 90 the connector switch circuit as shown, and relay S is connected between the middle point of such coil and one terminal of the battery B, the other terminal of such battery being grounded.

The enumeration of the different parts shown in the figure will be sufficient for a clear understanding of the operation of my invention as applied to an automatic connector circuit having automatic ringing.

Suppose the subscriber wishes to get into talking communication with another sub-

scriber whose number is 45. He sends four impulses over the tip side of his line causing the operation of the vertical relay A' and its magnet c' thereby stepping up the spindle U' until the wipers reach the fourth row. An impulse is then sent over the sleeve side of the line so as to operate the relay P' and its associated side switches, turning these side switches to their second position. The subscriber then repeats the operation, this time sending five vertical impulses and a rotary impulse as before. The five impulses operate the rotary relay A' and its associated magnet a', thereby turning the spindle and its wipers to the fifth contact on the row which connects the two subscribers. The line is then tested in the usual manner and if found busy, the release magnet operates to restore the switch to its normal position. If the line is not busy, the calling subscriber presses the button D' thereby actuating the vertical relay A', the current passing directly from the battery B' through the relay and to ground at the subscriber's station. The armature of the relay A' pulls up and in doing so closes contact at g' which thereupon establishes a circuit through the relays K' and J' by the following path: battery, 2', 3', 4', 5', g', 6', k', 7', 8', J', 9', K', 10, 11', contact 1' which is closed when the spindle U' is raised, and ground. The relay J' pulls up and puts current on the line through the contacts x' and z', the relay J' being locked through the contact y'. When the called subscriber responds, ground is put on both sides of his line momentarily by his hook switch, and the relay S is actuated through the coil M'.

In case the called subscriber does not answer, the armatures of the relay K' slowly pull up, taking say fifteen seconds for a full actuation. Before completing its travel the lower armature momentarily closes the contact n', and puts a ground on the relay S, which pulls up and locks through its armature e', the locking circuit being completed thus: battery, relay S, e', 11', 1', ground. When the relay K' has fully pulled up, depending upon the arrangement of the dashpot which may be constructed to operate in any desired time, a shunt is closed around the relay J' through the contact m' by the following path: battery 2', 3', 4', 12', m', K', 10', 11', 1', and ground. The relay J' lets go, cutting off the ringing current from the line.

The relay S being locked in the manner described and the contact being closed through the armature e, the line is now in condition for clearing out whenever the calling subscriber hangs up. When this is done a momentary ground is put on each side of the line as usual. The relays A' and C' both pull up and the release circuit is closed at v'. The

circuit at v' is closed before the contacts at g' engage. This actuates the release magnet R', the current flowing through the following path: battery, e, 13', 14', R', 15', 16', 17', v', 18' and ground. The release magnet R' operates to restore the switch to its normal condition.

It will be seen from the above description that after the calling subscriber has sent in the required signals and has set in operation the automatic ringing mechanism, he is then in condition to clear out whether the called subscriber answers or not.

Having thus described my invention, what I claim and desire to secure by Letters Patent is:

1. In a telephone exchange system, a calling and a called subscriber's line and an automatic switch for interconnecting the same, a release magnet for said switch normally disabled, and means controlled by the called subscriber in answering a call for removing the disability of said magnet and for rendering it operative for clearing out purposes.

2. In a telephone exchange system, a calling and a called subscriber's line and an automatic switch for interconnecting them, a normally disabled release magnet for the switch, a relay connected to the interconnecting circuit through said switch so as to be responsive to the act of a called subscriber, and a device responsive to the act of the calling subscriber for actuating said relay after a predetermined lapse of time only, said relay when energized acting to render the release magnet operative, and to keep it operative until the final release and restoration of the switch.

3. In an automatic telephone exchange system, a calling and a called subscriber's line, means for interconnecting them, a normally disabled means for restoring the connecting means to its inoperative condition, and means under the control of the called subscriber for removing the disability of the restoring means, such removal serving to deprive the called subscriber of further control over the connection.

4. In an automatic telephone exchange system, a calling and a called subscriber's line, means for interconnecting them, a normally disabled means for restoring the connecting means to its inoperative condition, and means under the control of the called subscriber for removing the disability of the restoring means, the operating circuit of such removing means extending from the called substation over both sides of the called line to the removing means and back to the called substation by means of a third conductor.

5. In an automatic telephone exchange system, a calling and a called subscriber's line, means for interconnecting them, a nor-

5 mally disabled means for restoring the connecting means to its inoperative condition, and a relay under the control of the called subscriber, such relay adapted by its operation to close one break in the energizing circuit of the restoring means when the called subscriber responds to the call.

6. In a telephone exchange system, a calling and a called subscriber's line, an automatic switch for interconnecting them, a release magnet for such switch, and a relay under the control of the called subscriber, such relay adapted by its operation to close one break in the energizing circuit of the release magnet when the called subscriber responds.

7. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet when the called subscriber responds, and means under the control of the calling subscriber for closing a second break in the release magnet energizing circuit and thus completing the same.

8. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet, such operation serving to lock the relay against further operation during the continuance of the same connection, and means under the control of the calling subscriber for closing a second break in the release magnet energizing circuit and thus completing the same.

9. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet, the operating circuit of such relay extending from the called substation over both sides of the called line in parallel to such relay and back to the called substation by means of a third conductor, and means under the control of the calling subscriber for closing a second break in the release magnet energizing circuit and thus completing the same.

10. In a telephone exchange system, a calling and a called subscriber's line, an automatic switch for interconnecting them, a release magnet for such switch, a relay under the control of the called subscriber, such relay adapted by its operation to close one break in the energizing circuit of the release

magnet when the called subscriber responds, and means under the control of the calling subscriber operative only after a predetermined interval for closing such break in the release magnet energizing circuit.

11. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet, such operation serving to lock the relay against further operation during the continuance of the same connection, and means under the control of the calling subscriber operative only after a predetermined interval for closing such break in the release magnet energizing circuit.

12. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet, the operating circuit of such relay extending from the called substation over both sides of the called line in parallel to such relay and back to the called substation by means of a third conductor, and means under the control of the calling subscriber operative only after a predetermined interval for closing such break in the release magnet energizing circuit.

13. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet when the called subscriber responds, means under the control of the calling subscriber operative only after a predetermined interval for closing such break in the release magnet energizing circuit, and means under the control of the calling subscriber for closing a second break in the release magnet energizing circuit and thus completing the same.

14. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet, such operation serving to lock the relay against further operation during the continuance of the same connection, means under the control of the calling subscriber operative only after a predetermined interval for closing such break in the release magnet energizing circuit, and means under

the control of the calling subscriber for closing a second break in the release magnet energizing circuit and thus completing the same.

- 5 15. In a telephone exchange system, a calling and a called subscriber's line, an automatic switch for interconnecting them, a release magnet for such switch, a relay under the control of the called subscriber, such relay adapted by its operation to close one break in the energizing circuit of the release magnet, the operating circuit of such relay extending from the called substation over both sides of the called line in parallel 10 to such relay and back to the called substation by means of a third conductor, means under the control of the calling subscriber operative only after a predetermined interval for closing such break in the release magnet energizing circuit, and means under the control of the calling subscriber for closing a second break in the release magnet energizing circuit and thus completing the same.
- 15 20 25 16. In a telephone system, the combination of a central station, a plurality of telephone lines leading into said central station, substations on said lines, one of said lines being a called line and another a calling

line, connecting mechanism, a normally disabled means for restoring the connecting means to its inoperative condition and means under the control of the called subscriber for removing the disability of the restoring means, such removal serving to deprive the called subscriber of further control over the connection.

17. In an automatic telephone exchange system, a calling and a called subscriber's line, means for interconnecting them, a normally disabled means for restoring the connecting means to its inoperative condition, and a relay under the control of the called subscriber, such relay adapted by its operation to close one break in the energizing circuit of the restoring means, the operating circuit of such relay extending from the called subscriber over both sides of the called line in parallel to such relay and back to the called substation by means of a third conductor.

In testimony whereof I affix my signature in presence of two witnesses.

WILLIAM W. DEAN.
